(57) **CLAIM**

The ornamental design for a stool, as shown and described.

DESCRIPTION

FIG. 1 is a perspective view of a stool according to my design;

FIG. 2 is a front elevational view thereof, the rear elevational, right side elevational and left side elevational views being identical thereto;

FIG. 3 is a top view thereof;

FIG. 4 is a bottom view thereof;

FIG. 5 is a perspective view of a second embodiment of the stool of my new design;

FIG. 6 is a front elevational view thereof, the rear elevational view being identical thereto;

FIG. 7 is a right side elevational view thereof, the left side elevational view being identical thereto;

FIG. 8 is a top view thereof; and,

FIG. 9 is a bottom view thereof.
